John A. Bonnhardt

ATTORNEY.

UNITED STATES PATENT OFFICE.

HENRY B. MEAD, OF CLEVELAND, OHIO.

RADIATOR CAP.

Application filed October 29, 1923. Serial No. 671,417.

To all whom it may concern:

Be it known that I, HENRY B. MEAD, a citizen of the United States, residing at Cleveland, in the county of Cuyahoga and 5 State of Ohio, have invented certain new and useful Improvements in Radiator Caps, of which the following is a specification.

This invention relates to improvements in radiator caps and has for an object the provision of a cap which may be readily and quickly attachable and detachable, and comprising a minimum number of operating parts whereby to simplify manipulation and manufacture.

15 Another object is to provide a radiator cap of this character in which is included a set of locking jaws or fingers adapted to be engaged with a radiator neck or other similar body, upon partial rotation of the 20 cap in one direction and disengaged upon reverse rotation.

Other objects will be in part obvious and in part pointed out hereinafter.

In order that the invention and its mode 25 of operation may be readily understood by persons skilled in the art, I have in the accompanying illustrative drawings, and in the following detailed description based thereon set out one possible embodiment of 30 the same.

In these drawings:

Fig. 1 is a partial side elevation of a radiator cap constructed in accordance with my invention.

35 Fig. 2 is a section taken on the line 2—2 of Fig. 3.

Fig. 3 is a section taken substantially on the line 3—3 of Fig. 2.

40 Fig. 4 is a view similar to Fig. 3, the locking jaws being shown in their locking position and the cap consequently having been partially rotated;

Fig. 5 is a bottom plan view of the movable frame, parts being broken away to 45 close the structure of the inner plate, and

Fig. 6 is a detail elevation of one of the locking jaws.

Having more particular reference to the drawings throughout which similar characters of reference designate similar parts this improved radiator cap may be stated

as comprising a main cap, oscillatively mounted upon a frame which is adapted to fit over a radiator neck or the like and which carries movable jaws or locking fingers engageable with said neck upon moving the cap in one direction and disengageable from the neck upon reverse movement of the cap.

As clearly indicated, the cap 7, includes a flat base portion upon which may be formed or attached any suitable or desirable ornament, and has a depending annular flange 8 which is adapted to surround and enclose the several parts making up this improved cap.

Formed integrally with the cap 7 and spaced equidistantly around the inner edge of the flange 7 is a set of shoulders or pins 9 which may be stated as constituting a means for engaging and disengaging the locking jaws or fingers and the body upon which the cap is arranged.

The cap is adapted to be removably and oscillatively mounted upon a frame which includes a base plate 10 centrally apertured for the reception of a connecting bolt 11 or other fastener which is extended through a similar opening in the main cap 7 and is secured in position by a locking nut 11' as shown in Fig. 2. This plate 10 as indicated in Figs. 3, 4 and 5 is provided

with cut-away portions whereby to provide ways 12 terminating in shoulders 13 by means of which oscillation of the cap is limited. As is apparent from Figs. 3 and 4 the shoulders or pins 9 carried by the cap and adapted to move the locking fingers, are positioned in these ways and are limited

as to their movement by the spaced shoulders 13. Spaced from the plate 10 of the removable frame, is a ring 14 which is secured to and spaced from the plate 10 by means of bolts or rivets 15, said bolts or rivets also serving as a means for mounting the several locking jaws or fingers within the frame.

The locking jaws or fingers 16 are mounted in the removable frame in sets, each set including any desired number of jaws, each of which is provided near one end with an opening 17, through which the aforemen-

tioned pin 15 passes. The inner face of the end portion opposite the apertured end of each jaw is screw threaded as indicated in Fig. 6, whereby to provide for interlocking engagement with the externally threaded neck portion of a radiator. It is understood that these locking jaws might have their inner faces differently formed for engagement with a body having a smooth outer face, depending upon friction to retain the parts in proper relative position.

When it is desired to attach this cap or closure to an externally threaded radiator neck, the cap is set down over the neck portion, the jaws being in the position shown in Fig. 3. Sufficient pressure is brought to bear upon the cap with the result that partial rotation in a clock-wise direction as between the cap and the jaw-carrying frame is possible so as to move the jaws inwardly into engagement with the threads on the radiator neck. By reference to Figs. 3 and 4 this operation and the resultant positioning of the jaws will be quite apparent. In order to insure relative movement between the cap and jaw-carrying frame, I have arranged upon the plate 10 a gasket ring 17, which is adapted to contact with the outer end of the radiator neck and under pressure upon the cap as a whole, serves to retain the frame against movement while the cap 7 is being partially rotated to lock the jaws. It is quite obvious that this means for attaching a closure to the radiator is quite effective and at the same time simple in operation and construction.

Manifestly, the construction shown is capable of considerable modification and such modification as may fall within the scope of my claims, I consider within the scope of my invention.

I claim:

1. In a closure of the character described, the combination of a cap, an annular member upon which the cap is arranged, an open frame oscillatively carrying said cap and mounted therewithin, a movable member carried by the frame, and means whereby upon partial rotation of the cap upon the frame, the said movable member will engage the annular member and upon reverse rotation of the cap, disengagement of the movable member will be effected.

2. In a closure of the character described, the combination of a cap, an annular member upon which the cap is arranged, a frame arranged in the cap, a set of movable members carried by the frame, means carried by the cap and engageable with the movable members, whereby upon rotation of the cap in one direction the members will engage the annular member and upon reverse rotation of said members will be disengaged from the said annular member.

3. In a closure of the character described,

the combination of a cap, an annular member upon which the cap is arranged, a frame movably arranged in the cap, a set of circumferentially spaced pivoted locking jaws carried by the frame, means carried by the cap for engaging the locking jaws to cause engagement or disengagement as between said jaws and said member upon oscillation of said cap.

4. In a closure of the character described, the combination of a cap, an annular member upon which the cap is arranged, a frame oscillatively mounting said cap, said frame comprising a base plate, a ring connected to and spaced from the plate, a set of movable members circumferentially spaced and arranged between the plate and ring, means carried by the cap and adapted to engage the movable members upon oscillation of said cap, said members being engageable with the annular member as and for the purpose set forth.

5. In a closure of the character described, the combination of a cap, adapted to engage over the externally threaded neck of a radiator, a frame arranged in and oscillatively mounting said cap, a set of locking jaws pivotally mounted in said frame and circumferentially spaced, said jaws having threaded faces to engage the neck, and means carried by the cap for causing engagement or disengagement as between said jaws and the neck.

6. In a closure of the character described, the combination of a cap, adapted to engage over the externally threaded neck of the radiator, an oscillatively mounted frame in the cap, movable locking jaws carried by the frame and engageable with the neck, means carried by the cap to cause engagement or disengagement as between the jaws and neck, and a gasket carried by the frame and adapted to engage the end of the neck to prevent water leakage and to insure movement of the cap upon the frame as and for the purpose set forth.

7. In a closure of the character described, the combination of a cap, a frame arranged in and oscillatively mounting said cap, said frame including a base plate, a ring spaced from said base plate, a set of circumferentially spaced pins connecting the base plate, a set of locking jaws pivoted to the pins and engageable with a radiator neck, and means carried by the cap to move the jaws into and out of engagement with the neck and means carried by the frame to limit the movement.

8. In a closure of the character described, the combination of a cap, a frame arranged in and oscillatively mounting said cap, said frame including a base plate, a ring spaced from said base plate, a set of circumferentially spaced pins connecting the base plate, a set of locking jaws pivoted to the pins and

engageable with a radiator neck, and means carried by the cap to move the jaws into and out of engagement with the neck, means carried by the frame to limit the movement, and a gasket ring arranged upon the base plate and adapted for engagement with the outer end of the radiator neck to prevent

water leakage and insure movement of the frame upon the neck with oscillation of the said cap.

10

In testimony whereof, I affix my signature.

HENRY B. MEAD.
